CLAIM

The ornamental design for the docking station as shown and described.

DESCRIPTION

FIG. 1 is a top, front, right perspective view of a docking station of our new design;

FIG. 2 is a bottom, rear, left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the figures depict portions of the docking station that form no part of the claimed design.
